H. J. KEMPF.
GUM WRAPPING MACHINE.
APPLICATION FILED DEC. 22, 1911.

1,092,149.

Patented Apr. 7, 1914.

UNITED STATES PATENT OFFICE.

HENRY J. KEMPF, OF SPRINGFIELD, MASSACHUSETTS, ASSIGNEE, BY MESNE ASSIGNMENTS, TO PACKAGE MACHINERY COMPANY, A CORPORATION OF MASSACHUSETTS.

GUM-WRAPPING MACHINE.

1,092,149.

Specification of Letters Patent. Patented Apr. 7, 1914.

Application filed December 22, 1911. Serial No. 667,319.

To all whom it may concern:

Be it known that I, HENRY J. KEMPF, a citizen of the United States of America, residing at Springfield, in the county of Hampden and State of Massachusetts, have invented new and useful Improvements in Gum-Wrapping Machines, of which the following is a specification.

This invention relates to package-wrapping machines and embodies certain improvements and changes in construction in a machine of the type shown in U. S. patent to A. M. Price on December 7, 1909, Number 942,101.

The present invention is closely related to applicant's co-pending application filed July 22, 1911, Serial Number 639,917. Only as much of the structure disclosed in that application as is necessary to an understanding of the present invention is described herein. The complete, specific operation of all the parts of the machine not described herein is brought out in said co-pending application and the patent to Price to which reference has been made.

The object of the invention is to provide mechanism for folding the wrapper ends over or under the packages as desired, or folding some of the ends over and some under the packages.

The wrapping of chewing gum is the specific object of the invention, although the mechanism can be applied broadly to wrapping machines in general.

In the drawings, Figure 1 is a side view of the assembled machine, with parts broken away to better show the relation of the parts. Fig. 2 is a detail perspective view of the end-folding mechanism.

Referring to the drawings, *a* represents two wheels around which an endless belt travels. These belts have peripheral pockets *b*, these pockets being made to receive a single one of the articles of which a predetermined number is to be bunched together and delivered into a pocket of the wheel *c* which is also provided with peripheral pockets *d*. The wheels *a*, have a continuous rotative movement to the left, and the wheel *c*, a step by step movement to the right. If five articles are to be bunched together, five pockets in the wheel *a*, will pass a given point between each step of the wheel *c*.

As set forth in the above referred to Price patent, suitable feeding devices, indi-

cated as a whole by *a*, located above and to the right of the chain carried by wheels *a*, will feed the single articles to be wrapped into the pockets *b*, of the chain, a suitable piece of wrapping material having been first placed over said pockets, and then a nipper *e*, is brought to bear against the forward edge of said piece, forcing the other edge of the latter back under an overhanging edge of the pockets, and thus between the nipper and overhanging edge. Both sides of the wrapper will be more or less turned over the opposite sides of said piece. An arm *g*, suitably formed to engage the partially upturned edges of the wrapper at this time, swings over the forward edge of the wrapper and down behind the rearmost edge, then sweeping forward, viz.—in the direction of the movement of the wheel, presses the rear edge of the wrapper indicated by *h*, down against the stick of gum and holds it down until the forward edge of the piece passes under the end of the curved strip *k*, lying above the chain, and thus folds the forward edge of the wrapper down over the other edge,—the arms *g* returning at the proper time. The plate *h*, is supported on two frame pieces not shown which extend transversely of the machine, the farther or left hand end of this plate extending a little beyond and between, two oppositely placed channeled plates *o*, lying around the chain as shown, also concentric with the wheel, and which receive the ends of the wrapped sticks. One of these channeled plates is seen in Fig. 2. The ends of the sticks of gum, after the ends of the wrapper have been folded over them, enter and follow these channeled plates *o*, whereby the end folds of the wrapper are held in place.

The mechanism, whereby the ends of the wrapper are folded over the ends of a certain number of sticks in one direction consecutively and then folded over the ends of a single stick in the opposite direction, occupies a position between the two parts *h* and *o*, and has a vertical movement straight up and down, due to the cam 17 and the link motion 18 and *g*. The cam 17 is controlled by the shaft of the feeding device *a*, so that a movement of the end-folding mechanism up or down takes place for a certain movement of the feeding device. In wrapping gum it is usual to time the movements so that every fifth stick has its end folds re-

versed from the preceding four. The end-folding mechanism (see Fig. 2) just referred to, comprises two jaws, t and v , on each of the arms for folding the ends of the wrapper over or under the sticks, the jaws being oppositely located and spaced apart, and in the space between the jaws is a roll w , having its end formed into a beveled flange x , there being just room between the edge of this flanged head and the jaws t and v , above and below, to permit the extended ends of the wrapper to pass, and in passing, to have a folding line creased therein. The walls of the jaws t and v , are so formed with beveled or recurved surfaces y extending into the path of the ends of the wrappers, that after the crease line has been formed therein, these ends will be turned over the stick of gum, as the movement of the chain carries it between the jaws, it being understood that said beveled surface y , in the lower jaw v , is so made as to turn the ends of the wrapper up and over the stick, and the like surface on the upper jaw t so formed as to turn them down and under the stick. It is therefore plain that by holding the end-folding mechanism down in such position that the ends of the wrappers of a certain number of sticks will be turned under, and then shifting said mechanism, will cause the next stick to have the ends of its wrapper turned up and over. When a group or bunch of the sticks have been gathered together by this transverse mechanism and shifted into one of the pockets of the wheel c , we shall have them arranged in said pocket so that the folded ends of the wrapper on each stick of the bunch will be held against displacement during subsequent operations.

Referring now to the transfer mechanism: it will be understood that this mechanism is in every detail like that described in applicant's co-pending application hereinbefore referred to. It comprises a curved trough 3 , the upper end of which lies about opposite the point where each pocket b , will pass during the movement of the chain, while the lower end of the trough will be opposite a pocket d in the wheel c , when that wheel is at rest. As each of the pockets, b , passes the transfer trough, the hooked arm 4 on the rock-shaft 5 moves down and engages the edge of the stick of gum caught under the lip f of the pocket, the arm e (which up to this time has held the gum in the pocket) engaging with an operating cam (not shown) and swinging down against the action of a spring (not shown), provides a support for the lower edge of the stick. Owing to the angle of the arm 4 and its relation to its axis, viz.—the shaft 5 , it will be so moved that after a slight downward movement, as described, it will swing forward and push the stick of gum past two spring clips 6 , located in the path of the ends of the stick and supported on the

two side plates 8 , which constitute an extension of the two sides of the trough 3 . A swinging frame 9 is hung on shaft 10 , on an arm 12 of the frame, and comprises two arms which are pressed forward by a spring 13 to bring their ends near the wheel a , and just back of the spring clips 6 . Beyond and a little below, these clips are two other clips 14 , oppositely located in the plates 8 , and having beveled ends which extend into the trough in the path of the sticks of gum, these beveled ends serving to hold up the several sticks as they are grouped together before being transferred as one piece into a pocket of the wheel c . As the units constituting the group are one by one transferred as described, from the pockets b , of the chain, they are positioned under the end of another swinging frame 15 , mounted on a shaft 16 concentric with the curved transfer trough 3 , and this frame just fits the space between the two sides of the latter, and the space between the ends of the two depending arms of the frame 9 . The frame 15 is at the proper time given a rocking movement by mechanism not shown herein but fully shown in the co-pending case referred to. The sweep of the frame 15 is such as to carry the group of sticks through the trough 3 and push the same into a pocket d of the wheel c which, at the proper time, becomes stationary opposite the delivery end of the trough. When the swinging frame 15 pushes the grouped sticks of gum into the trough, it forces the ends thereof past the beveled ends of the clips 14 , which then snap back into position to receive other sticks of gum.

The wheel c , which receives the sticks of gum in groups in the pockets d , as described, has mechanism associated therewith to apply wrappers to the sticks, a little narrower than the sticks, leaving the ends of the latter exposed, all of which mechanism is identical with that described in said co-pending application.

The pockets d are rectangular recesses extending across the periphery of the wheel, one of the sides of the pockets consisting of a plate 20 spring-pressed toward the opposite side, and back of each pocket is a hollow spoke 21 of the wheel, in which is a plunger 22 having a rectangular head 23 . The plungers 22 are actuated by a cam not shown, the latter being so formed that at a point substantially opposite that at which the package of sticks of gum is placed in one of the pockets, the plungers 22 will be successively actuated to expel the package into a straight receiving trough 50 , and from this point the head of the plungers 22 will be maintained flush with the periphery of the wheel around to the point at which the pocket is to receive another package. Just before this point is reached the cam frees the plunger and allows it to be pushed

in radially by the package. The outside wrappers for the package of grouped sticks of gum are stacked in the container 51. They are delivered one by one, the cam 32 and parts 29 and 29^a aiding in the operation, as described in the aforementioned application. It will be seen that the length of the wrapper is such that its rear end will overlie, and extend some distance beyond the next following pocket, which is the pocket which will receive the package of gum this wrapper is destined to inclose, and that part of the wrapper which covers the area of the box *d* and extends somewhat to the rear thereof, is sufficient to nearly inclose three sides of the package. Before the pocket which has had placed therein a package of gum, arrives at the position directly under the shaft 36 on which the wheel *c* is supported, and where the gumming devices are located, the nipper which holds the front end of the wrapper is tripped by cam 32 and the wrapper allowed to fall forward and downward as shown, to the end that when it reaches the gumming devices, it will hang straight down in front of the plate 37, and while in this position the gum roll 38 carried by the arm 39¹, will be swung up against the lower edge of the wrapper and the gum roll will remain in contact therewith until another rotative movement of the wheel draws the wrapper forward, rotating the gum roll and applying gum from the point where the roll first touches the wrapper to the extreme end thereof. To insure good contact between the gum roll and the wrapper, the plate 37 is hinged at its upper end and its lower end is held out by a spring 40 to meet the gum roll and yield slightly when the roll comes in contact with it. After the gum roll has been applied to a wrapper, the gum roll is swung into the gum box 42 and takes up another supply of gum for the next wrapper. The gumming mechanism is well known and *per se* forms no part of the invention.

From the point where gum is applied to the wrapper to the point of delivery of the sealed package, viz.,—one-fourth of one complete revolution of the wheel,—the periphery of the latter is encircled by a plate 39 concentric therewith and set as close to the wheel as necessary to hold the gummed end of the wrapper in position to be wrapped around the package when the latter is ejected from its pocket and pushed into the delivery trough 50, this ejection and trans-

fer serving to press the free gummed end of the wrapper against the opposite end thereof. This is made by the cam previously mentioned as described and the plunger 22 and at the mouth of the delivery trough two rolls 45 are mounted, transversely thereof, between which the package is forced, the lower of the two rolls being fixed and the upper being mounted in a plate 46, spring-pressed down against the packages as they are successively forced into the trough, thus pressing the gummed end of the package to a seat on the package.

Claims.

1. In a wrapping machine, mechanism to successively fold a wrapper around articles fed into the machine, other mechanism for bunching together a predetermined number of such articles to constitute a package, together with end-folding mechanism interposed between said wrapping and bunching mechanism and means to intermittently reciprocate said end-folding mechanism in a straight line to successively fold the ends of the wrappers inclosing said articles over the ends of certain of them in one direction and over the ends of certain others of said articles in the opposite direction.

2. In a wrapping machine, mechanism to successively fold a wrapper around articles fed into the machine, other mechanism for bunching together a predetermined number of such articles to constitute a package, together with end-folding mechanism interposed between the wrapping and bunching mechanism and comprising a member having a straight line movement across the path of the articles passing through the machine, means for folding the ends of the wrappers in opposite directions over the ends of the articles being located in different parts of said member, means being provided to move said member at predetermined intervals.

3. In a wrapping machine means to fold a wrapper about an article fed into the machine together with end-folding devices arranged when in one position to fold the ends of the wrapper over the ends of the article in one direction, and means to shift said devices in a straight line to another position in which they are arranged to fold the ends of the wrapper over the article in another direction.
